UNITED STATES PATENT OFFICE.

HENRY E. VAN NESS, OF ELMIRA, NEW YORK, ASSIGNOR TO ECLIPSE MACHINE COMPANY, OF ELMIRA, NEW YORK, A CORPORATION OF NEW YORK.

ENGINE-STARTER PINION.

Application filed February 11, 1921. Serial No. 444,103.

To all whom it may concern:

Be it known that I, HENRY E. VAN NESS, a citizen of the United States, residing at Elmira, county of Chemung, State of New York, have invented Improvements in Engine-Starter Pinions, of which the following is a specification.

My invention relates to a two part element of any kind and a new and useful method of permanently connecting them together. In practice my invention is used in connection with the manufacture of the driving member such as a pinion of the drive or transmission of an engine starter in which such invention finds useful application and for the sake of a clear and definite description of my invention I will herein-after describe it in connection with such particular use without intention of limiting myself thereto. In the particular use shown the two parts of the element or pinion consist of the pinion proper and the weighted disk which is made separately therefrom and attached thereto according to the method hereinafter explained with the result that the two parts are mechanically permanently connected by machine operations which are comparatively simple and economical.

In the drawing Fig. 1 is an elevation of the inner end of the pinion proper; Fig. 2 a side elevation thereof with a portion in section; Fig. 3 an end elevation of the disk; Fig. 4 an end elevation of the disk showing the same applied to the pinion but not yet pressed to place; Fig. 5 a section on the line 5—5 of Fig. 4; Fig. 6 a view similar to Fig. 5 but illustrating the element or structure in completed form; Fig. 7 a section on the line 7—7 of Fig. 3 and Fig. 8 a cross section of an element or pinion which is modified to the extent of omission of the internal screw threads, and the provision of a plain or unweighted disk.

Referring to the particular embodiment of my invention herein selected for a disclosure of my invention the element consists of two parts, to-wit, a pinion 1 and a weighted disk 2 which is in the form of a ring. This ring is to be permanently secured in mechanical manner to the pinion proper by the means and in the manner now to be explained. One form of the pinion structure and its use are exemplified by United States

Patent No. 1,274,369 issued on August 6, 55 1918 to Vincent Bendix, for improvements in engine starters.

The pinion is transversely grooved by suitable machine operations such as milling thereby forming a series of grooves which 60 are here four in number. Each groove 3 has under-cut sides 4 and in addition a central outwardly directed preferably sharpened wedge constituting a chisel in its action. By preference, the bottoms of the 65 grooves are inclined inwardly from the lower ends of the wedge proper to the inner ends of said undercuts. Also the pinion teeth are cut back at one end as indicated at 6 to form a mounting for the disk 2. 70

The ring 2 which is provided with the over-balancing weight 7, integral therewith, is provided with a series of inwardly directed radial lugs 8 which correspond in number to the number of the grooves 3, so that 75 in the present instance there are four of these lugs. These lugs are of a size to substantially fill the grooves 3 and the same are adapted to be expended or spread laterally in said grooves and tightly against the sides 80 of such grooves which by preference are under-cut as hereinbefore described in order to make the mechanical connection between the two parts most effectual.

The two parts being made as above described are now placed in a proper machine tool such as a press. At this time the two parts are assembled as shown in Figs. 4 and 5 with the lugs 8 in register with the grooves and when the press is thereupon operated 90 the lugs 8 will be forced inwardly into such grooves and the wedges or chisels 5 will bite into these lugs, preferably, only partially thereinto, and will cause a distortion of the lugs and then a spreading of the 95 inner portions thereof laterally against the side walls of the grooves and into the undercuts 4 by reason of the inclination of the bottoms of the groove. The result of this method is the element or completed weight- 100 ed pinion shown in Fig. 6.

In Fig. 8 I have shown a modified form of element which is the same as that above described with exception that the disk 9 is unweighted and pinion proper marked 10 is 105 not provided with any internal screw threads such as the threads 11 in Fig. 6 but provided with a smooth bore 12 for use on

a somewhat different type of drive in which such pinion is not screw threaded upon a shaft. The pinion and its disk are thereby held securely together against displacement both longitudinally and rotarily.

I claim:

1. An engine starter pinion comprising a body portion having a central bore and provided on one end with transverse grooves 10 having outwardly directed sharpened wedges in the middle portion of the base of the grooves, such grooves having straight but inclined sides to form undercuts at the base thereof, and a disk portion having inwardly 15 extending radial lugs adapted to fit into the grooves and onto the wedges which split the lugs and spread the mass thereof against the sides of the grooves and into the undercuts, whereby the disk portion and body 20 portion are held tightly together against

displacement both longitudinally and rotarily.

2. An engine starter pinion comprising a body portion having a central bore and provided on one end with transverse grooves 25 having outwardly directed sharpened wedges in the middle portion of the base of the grooves, such grooves having straight but inclined sides to form undercuts at the base thereof, and the base of the grooves sloping 30 outwardly from the base of the wedges to the inner corners of said undercuts, and a disk portion having a series of inwardly extending radial lugs adapted to fit into the grooves and onto the wedges which split the 35 lugs and spread the mass thereof outwardly, the inner ends of the split lugs contacting the sloping bases of the grooves and being thereby directed into said undercuts.

HENRY E. VAN NESS.
